Specification for Design.

Patented Aug. 10, 1920.

Application filed April 12, 1919. Serial No. 289,748. Term of patent 14 years.

To all whom it may concern:

Be it known that I, JOHN L. CHESNUTT, a citizen of the United States of America, and resident of Kansas City, in the county of Jackson and State of Missouri, have invented a new, original, and ornamental Design for Swivel-Casters, of which the following is a specification, reference being had to the accompanying drawing, forming part thereof.

Figure 1 is a perspective and Fig. 2 an end elevation of a swivel caster, showing my new design.

I claim:

The ornamental design for a swivel caster, as shown.

JOHN LOUCIEN CHESNUTT.
